METHOD OF AND MEANS FOR HANDLING
COILS OF WIRE

Leonard G. Berquist, Niles, Mich., assignor, by mesne assignments, to Clark Equipment Company, Buchanan, Mich., a corporation of Michigan

Application March 5, 1956, Serial No. 569,430

4 Claims. (Cl. 214—620)

The present invention relates to a method and means for lifting and transporting coils of wire and, while not expressly limited to that purpose, is particularly adapted to transport said wire coils to and from a work station such, for example, as an annealing furnace.

In the program of fabricating wire and the like, including cables, metal ribbons, etc., such materials are normally made up in the form of annular coils and secured by banding means. It will be appreciated that such coils are necessarily cumbersome and heavy. As a result, the problem of moving them in and about a factory and, for example, to and from the annealing furnace is a troublesome one.

Various coil grippers are now known employing expansion systems whereby a core mechanism or the like may be inserted within the open hollow center of the fabricated coil and expanded to grip the interior side walls of the coil. Such grippers are provided with hoist attaching means for connecting the gripper to conventional hoist means for the lifting of the coil by the latter. These coil grippers are objectionable from the standpoint of being limited to the movement of a single coil at any one time, and to the expense and inefficient use of the hoist mechanism need to transport the coil.

Broadly, the present invention has for its principal object the provision of means whereby a series of coils may be lifted and transported as a unit.

Specifically, the invention contemplates the provision of means whereby a series of coils in side-by-side relationship with their axes aligned in a horizontal plane may be engaged by said means and tilted thereby so that the axes of the coils of wire lie in a vertical plane for transportation of the coils.

Briefly, the above and other objects of the present invention contemplate the utilization of a conventional lift truck in conjunction with an expandable prong or ram pivotally mounted on the lift carriage of the truck. The prong or ram is provided with means to lock it in a lower horizontal position and preferably with its axis axially aligned with the open centers of a series or group of coils. Upon forward movement of the truck, the prong or ram may be inserted in the open centers of the coils. Mechanism is then extended over the outermost coil at the free end of the ram to prevent the coils from passing thereoff. By releasing the locking means holding the ram in its horizontal position, and by elevating the lift carriage to which the ram is attached, the series of coils may ultimately be disposed with the axes thereof in a substantially vertical or perpendicular position. The series of coils in such vertical position may then be transported by movement of the truck to a point, for example, over the annealing stem of an annealing furnace, which latter may typically be located in a pit below the floor supporting the truck. The annealing furnace has a vertically movable loading platform, and with the lift truck and coils positioned as described, by retracting or releasing the mechanism extended over the outermost coil at the free end of the ram, the series of coils may be disposed on

2

the loading platform whereby upon lowering of the platform the coils will be stripped from the ram and transferred to the annealing stem. It will be obvious that by carrying out the above operations in reverse order that 5 a series of coils may be transferred from the annealing stem to the prong or ram and transported to a place of storage.

Other features and advantages of the invention will in part be obvious and in part will hereinafter appear and 10 they consist generally in the features of construction, combinations of elements, and arrangements of parts, which will be exemplified in the construction to be described and of which the scope of application will be indicated in the appended claims.

15 In the accompanying drawings in which is shown the preferred illustrative embodiment of the invention:

Figure 1 is a side elevational view of a fork lift truck equipped with a pivotal prong or ram for the purpose hereinbefore described;

20 Figure 2 is a view similar to Figure 1 showing the lift carriage of the truck transposing a series of coils from a horizontal to a vertical position; and

25 Figure 3 is a side elevational view of the lift truck and ram of the present invention showing the series of coils positioned in a vertical position over the annealing stem of an annealing furnace.

Referring now in detail to the drawings, the lift truck 1 is a known type of commercial vehicle having the usual uprights 2 at the forward end thereof in which operates 30 the usual lift carriage 3.

The prong or ram 4 is supported on the lift carriage 3 by brackets 5 that may be secured to the carriage in any suitable or preferred manner. The ram is pivoted, adjacent one end, between the brackets 5 on a pivot pin 35 or shaft 6 for pivotal movement from a horizontal to a vertical position. To provide for holding the ram in a lowered horizontal position the rearward extension 4a of the ram is provided with the recess 7 for receiving a locking pin 8, which pin operates in a slot 9 in the brackets 5. Locking pin 8 may be manually operated for unlocking ram 4 from brackets 5, or it may be hydraulically actuated from the truck operator's seat for that purpose. Preferably, the pin and recess are so designed that the pin 8 will automatically engage in recess 7 upon movement 45 of the ram from its vertical to its horizontal position.

Ram 4 comprises a metal tube 10 of appreciable length, and provided with a plurality of circumferentially spaced brackets (three in this instance) at the end thereof adjacent pivot pin 6. Ribs 11, of a length slightly less than tube 10, are pivotally mounted at 12 to such brackets. At its opposite free end each rib has one end of an outwardly curved shoe 13 pivoted thereto at 14, the free end of which is adapted to partially engage over the outer surface of the outermost coil at the free end of the ram.

55 To expand the ram, that is to move the ribs 11 outwardly about their pivots 12, an expander, designated generally at 15, is employed. Such expander comprises three links 16 having one end pivoted at 17 to the shoes 13, the other ends of the links extending through a slot 60 into the tube 10, where they are connected to hydraulic actuator mechanism (not shown) located within the tube. Also, the expander includes three links 18 pivoted at 19 to brackets 20 spaced circumferentially about and secured to the outer surface of tube 10. A cam member 21 formed on each of links 18 extends through a slot in tube 10 and has camming engagement with a roller (not shown) connected to the hydraulic actuating mechanism in the tube. Also, the links carry a roller (not shown)

65 journaled thereto at 22, this roller having bearing and rolling engagement with a recess 23 in links 18. The operation of the expander is such that upon initial move- 70

ment of the hydraulic actuator, the shoes 13, which normally lie in a slot in tube 10 in the retracted position of the expander, are initially moved outwardly about their pivots 14, after which the roller connected to the hydraulic actuator comes into contact with the cam 21 on links 18. Then, upon continued actuation of the hydraulic actuator, the aforementioned roller and cam 21 become operative to swing ribs 11 outwardly about their pivots 12 relative to tube 10, through the medium of the roller journaled to the links 18 at 22, until such time as the free ends of the ribs are in contact with the inner surface of the outermost coils on the ram and with the shoes 13 partially engaging the outer vertical face of the outermost coil on the ram.

The details of construction of the above described expander are not of the essence of the present invention, as any suitable expander may be employed to swing the ribs 11 outwardly about their pivots 12 for the purpose described. However, the details of construction of such expander are fully illustrated and disclosed in the pending application of Fred Sherriff, Serial No. 569,843, filed March 6, 1956, for Coil Handling Device, to which application reference may be made, if desired.

In operation of the device of the present invention, the truck operator will first lock the ram 4 in its horizontal position, if it is not already so locked, through the medium of pin 8 and recess 7. The ram 4 may then be raised or lowered relative to uprights 2 to axially align the ram with the open centers of a plurality of wire coils 24 that are to be transported to a work station such as an annealing furnace 25. The truck 1 is then driven forward to position the ram 4 in the bore of the coils. By then actuating expander 15, the ribs 11 may be caused to swing outwardly about their pivots 12 to position the free ends of ribs 11 against the inner surface of the outermost coils on the ram and the shoes 13 partially over the outer surface of the outermost coil on the ram. The coils and ram are then ready to be transferred from a horizontal to a vertical position.

In elevating the ram and the coils from the horizontal position to the vertical position, it is to be observed that it is not contemplated that such change from the horizontal to the vertical position would be accomplished by simply elevating the ram in its horizontal position and thereafter releasing lock pin 8 from its recess 7, thus allowing ram 4 to pivot to its vertical position. Such a sequence of operations would allow the ram and coils to swing downwardly very rapidly with possible damage to the truck supporting structure. On the contrary, in moving the ram and coils from their horizontal position to their vertical position, it is contemplated that after the coils are positioned on the ram in its horizontal position, the truck operator will then release lock pin 8 from recess 7 and will then gradually raise lift carriage 3, thus allowing the outermost coils to slide along the floor until the ram assumes its vertical position. In lieu of sliding the coils along the floor, the truck operator may, if he so desires, inch the truck forwardly consistent with the rise of the lift carriage in the uprights 2.

It will be observed that the placing of the coils of wire in an annealing furnace is essentially a two level operation. The annealing furnace 25 is positioned on the lower level, with the truck carrying the wire coils on the level thereabove. Upon arrival of the truck and the superposed coils at the furnace, the ram is disposed in contact with the annealing stem 26 of the furnace.

As shown, annealing furnace 25 has a vertically movable platform 27, which is raised to its upper limit to receive the coils on the ram. The truck operator by retracting expander 15 will release ribs 11 from the coils 24 to allow them to be deposited on platform 27. Upon lowering platform 27, the coils will be transferred from the ram 4 to the annealing stem 26.

It will be obvious that the operations described above may be carried out in reverse order, that is, the truck and

ram (the latter free of wire coils and the ribs 11 retracted) may be positioned with the ram 4 over annealing stem 26. By then raising platform 27 with a load of wire coils thereon, the coils may be transferred from the annealing stem 26 to the ram 4. Ribs 11 may then be expanded to hold the coils fast to the ram. The truck can then be driven to a point of storage where, by resting the lowermost coil on the floor or storage rack 28, the truck may be backed away and the lift carriage simultaneously lowered to dispose the coils with their axes in a horizontal position. By locking the ram in its horizontal position and then further backing the truck, the ram may be removed from the centers of the coils.

While a preferred form of the invention has been illustrated and described by way of example, it will be obvious that changes may be made therein within the spirit and scope of the invention. For example, the ram instead of being pivoted from its horizontal to its vertical dependent position, may swing, by suitable means, from its horizontal position to a vertically upwardly extended position where the load may be removed from the ram by overhead equipment for processing. Therefore, the invention is not to be limited to the precise form herein disclosed, except insofar as it may so be limited by the appended claims.

I claim:

1. A method of handling a group of wire coils with a lift truck having an upwardly and downwardly movable carriage provided with a ram, which comprises the steps of positioning a group of coils of wire in side-by-side relationship with their axes aligned in a horizontal plane, engaging the ram in the openings in the group of coils, elevating the movable carriage to suspend the group of coils on the ram with their aligned axes in a vertical plane, transporting the group of coils so suspended to a work station, and lowering the movable carriage to lower the group of coils at the work station to a position where the uppermost coil of the group of coils is disposed below the horizontal plane in which the axes of the coils initially laid.

2. For use with an industrial truck having an upwardly and downwardly movable load supporting carriage, the combination of ram means with one end being pivotally mounted to the load supporting carriage and normally maintained in a horizontal position for engagement of the other end thereof into at least a single coil of material having its axis positioned in a horizontal plane, said ram means being operable from its normal horizontal position to a dependent vertical position with respect to said load carriage upon upward movement of the latter, and means carried by said ram means expandable after the latter has been inserted into the coil of material to prevent the coil from thereafter passing off of the ram means.

3. For use with an industrial truck having an upwardly and downwardly movable load supporting carriage, the combination of ram means with one end being pivotally mounted to the load supporting carriage and normally maintained in a horizontal position for engagement of the other end thereof through an opening in a coil of material having its axis positioned in a horizontal plane, said ram means being operable from its normal horizontal position to a dependent vertical position with respect to said load supporting carriage upon upward movement of the latter, and means carried by said ram means having elements expandable from an effective diameter less than, to an effective diameter greater than, the diameter of the opening in the coil after the elements have been passed through the latter to prevent the coil from thereafter passing off of the ram means.

4. The device of claim 3, wherein the ram means comprises a tube, a plurality of circumferentially spaced brackets mounted on one end of said tube, a rib pivoted at one end to each of said brackets, and means cooperating with said tube and said ribs to swing the opposite

end of said ribs outwardly about their pivots relative to
said tube.
